UNITED STATES PATENT OFFICE

152,156

DESIGN FOR A RADIO RECEIVER CABINET

Albert L. Jenks, Dixon, Ill., assignor to Motorola,
Inc., Chicago, Ill., a corporation of Illinois

Application August 23, 1947, Serial No. 141,026

Term of patent 7 years

(Cl. D56—4)

To all whom it may concern:

Be it known that I, Albert L. Jenks, residing at 217 South Galena Street, Dixon, in the county of Lee, State of Illinois, have invented a new, original, and ornamental Design for a Radio Receiver Cabinet, of which the following is a specification, reference being had to the accompanying drawing, forming a part thereof in which:

Fig. 1 is a front perspective view of a radio receiver cabinet, embodying my new design and shown with the front cover closed; and

Fig. 2 is a corresponding view thereof with the front cover raised.

The characteristic features of my new design are shown in solid lines in the drawing.

The back side of the cabinet, which is not shown in the drawings, is plain.

I claim:

The ornamental design for a radio receiver cabinet, substantially as shown and described.

ALBERT L. JENKS.
